Application September 27, 1935, Serial No. 42,371

10 Claims.

(Cl. 60—95)

My invention relates to marine turbines having ahead and astern sections and it has for its object to provide means to limit the temperature of steam exhausting from the astern section in order 5 to avoid structural distortion and excessive stresses which may occur because of excessive temperatures of such steam.

In the marine turbine art, it is common practice to design the ahead turbine section to secure 10 most economical performance with steam supplied under given or existing conditions. Also, it is usual to supply steam from the same source or boiler to the astern section or sections. As an astern section is very much shorter than an 15 ahead section and is usually not as efficient, so far as converting heat energy into mechanical energy is concerned, it will be apparent that heat energy in steam supplied to the astern section will manifest itself as superheat in the exhaust 20 even though the astern and ahead sections are designed to expand steam down to approximately the same absolute pressure. Excessive superheating of steam exhausting from the astern section, or relative high temperature of such steam, 25 may be objectionable on account of the consequent localized heating of the turbine structure setting up distortion, differential expansion effects, and severe stresses. To avoid undesirable effects of superheating, I bring a suitable medium, such as water, into heat transfer relation 30 with respect to steam passing through the astern section in order to limit the temperature of such exhaust steam. Accordingly, a further object of my invention is to provide cooling apparatus arranged in this manner and for the purpose indicated.

A further object of my invention is to provide a marine turbine having ahead and astern sections with means for spraying water into steam 40 passing through the astern section in order to limit the exhaust temperature of such steam.

A further object of my invention is to provide a marine turbine having forward and astern sections exhausting to a condenser together with 45 a device for spraying water into steam passing through the astern section in order to limit the exhaust temperature of such steam, the spray device being supplied with condensate from the condenser.

50 A further object of my invention is to provide a marine turbine having forward and astern sections and a device for supplying a spray of water to the steam passing through the astern section in order to limit the exhaust temperature of such steam, the valves controlling the supply of steam

to the astern section and of water to the spray device being interconnected so that operation of the astern steam valve will result in operation of the water valve.

These and other objects are effected by my 5 invention, as will be apparent from the following description and claims taken in connection with the accompanying drawing, forming a part of this application, in which:

Fig. 1 is a side elevational view of a marine 10 turbine installation having my invention applied thereto;

Fig. 2 is a vertical transverse sectional view taken along the lines II—II of Fig. 1;

Fig. 3 is a longitudinal vertical fragmentary 15 sectional view; and,

Figs. 4 and 5 are sectional views showing alter- 20 native locations of the spray device.

Referring now to the drawing more in detail, I show a marine turbine, at 10, having a casing 20 25 including upper and lower parts 12 and 13. A rotor 14 is disposed within the casing.

Ahead and astern blading sections 15 and 16 are carried by the casing and by the rotor, the sections being supplied with steam by the conduits 17 and 18, respectively; and, as shown in Figure 3, the sections are so arranged as to discharge into a common exhaust space 20 enclosed by the casing.

The turbine, at 10, is arranged to exhaust into 30 a condenser 21 in the usual way, the condenser having a hot-well 22 from which condensate is removed by the pump 23 and discharged through a pipe 24 for return to the steam generating apparatus.

35 Since it is undesirable to construct the turbine any longer than necessary and since the astern section is used very little compared to use of the ahead section, it is the common and reasonable practice to make the astern section relatively 40 much shorter axially compared to the ahead section, the astern section containing a relatively smaller number of rows of blades or energy-absorbing elements. Therefore, if the ahead section blading is designed to expand steam from 45 boiler pressure down to a desired absolute or condenser pressure with a desired exhaust temperature, it will be apparent that, with steam supplied from the boiler to the astern section, even though the pressure may be reduced in the astern section 50 to approximately the same value as the pressure of the ahead section exhaust, the heat energy in the steam will not be as efficiently utilized or converted into mechanical energy, with the result that such heat energy will manifest itself as 55

superheat in the steam exhausting from the astern section. Because of structural difficulties which may be encountered on account of superheat, or high temperature, of steam exhausting from the astern section, I propose to bring a suitable medium into heat transfer relation with respect to steam passing through the astern section in order to limit the temperature thereof.

The temperature of steam exhausting from the astern section is preferably limited by means of a spray device 25 arranged so as to discharge a spray of water into steam exhausting from the astern section in order to limit the temperature of such steam. In Figs. 2 and 3, I show the spray device 25 supported interiorly of the casing 11, extending circumferentially of the exhaust ends of the blading sections and arranged so as to be out of the way of the steam exhausted from the latter. As shown in Figs. 2 and 3, the spray device is arranged radially outward from the exhaust end of the ahead section and is so disposed that the water jets 26 thereof may be directed rearwardly toward the exhaust end of the astern section in such manner that the spray may freely enter the common exhaust space 20 between the turbine sections and absorb superheat of steam exhausting from the astern section, the heat of superheat being used to heat and vaporize the water. Since it is customary to have the turbine casing comprised by upper and lower detachably-connected parts, I prefer to construct the spray device 25 in such manner that it is comprised by semi-circular tube sections 27 and 28 carried by the upper and lower case parts 12 and 13, respectively.

In Fig. 4, I show a modified form of spray device including a belt tube 29 encompassing the stator element 30 of the astern section 16 and having spray openings 31 arranged to discharge water toward and into the space between the ahead and astern blading in order that steam issuing from the astern blading may be de-superheated.

Instead of having the spray device discharge a spray of water into steam exhausting from the astern section, as indicated in Figs. 2, 3, and 4, the spray device may be arranged to supply water into the steam before it is exhausted from the astern section with the result that superheating is limited. To this end, in Fig. 5, I show a tubular spray device 32 arranged to discharge jets of water into the steam issuing from the nozzles 32a of the astern section. Since the velocity of steam issuing from such nozzles is more than adequate for the blading, no material interference is set up because of water injection in this manner and at the same time the water so injected is effective to limit the temperature of the exhaust.

Water may be supplied to the spray device in any suitable manner; however, care should be exercised with respect to the temperature of the water if the invention is to be used to the best advantage, for, if the water temperature is appreciably below that of the temperature corresponding to the vacuum, there would be undesired chilling resulting in differential temperature effects on the structure similar to those already described. Furthermore, where a surface condenser is employed, as is usually the case with marine installations, the spray water should be suitable for boiler feed; and, while any feed water having the desired temperature may be used, condensate from a surface condenser meets both the temperature and feed water requirements. The temperature of the water injected should ap-

proximate normal exhaust temperature of the ahead section. Consequently, I prefer to use condensate from the condenser in the spray device, the heat or superheat being absorbed by vaporization of the condensate and the latent heat of such vapor being carried away by the condenser circulating water in the usual way. In Fig. 1, I show a conduit 33 for supplying condensate to the spray device; and, since I prefer to have the spray device made into upper and lower parts, 10 the conduit 33 has branches 34 and 35 leading to the upper and lower spray conduits 25 and 26.

It is desirable that the astern section and the spray device therefor shall be operated together. Accordingly, in Fig. 1, I show the steam conduit 18 for the astern section provided with a control valve 36 which may be opened and closed by a suitable operating device 37. Also, the condensate conduit 33 has a valve 38. Any suitable interconnecting mechanism, at 39, may be arranged between the valves 37 and 38 so that, when the valve 37 is open and closed the spray valve 38 will also be opened and closed.

From the foregoing, it will be apparent that I have devised a marine turbine arrangement 25 wherein excessive temperature, or superheat, of steam exhausting from an astern section is avoided, this result being effected by means of water injected in the steam passing through the astern section, the water being vaporized by heat derived from the steam so as to limit the temperature of the latter.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. The combination with a marine turbine having ahead and astern sections and a surface condenser to which the sections exhaust, of means 45 for supplying steam to the sections and means for bringing condensate delivered from the surface condenser into heat transfer relation with respect to steam passing through the astern section to limit the temperature of steam exhausted 50 therefrom.

2. The combination with a marine turbine having ahead and astern sections and a condenser to which the sections exhaust, of means for supplying steam to the sections, a spray device for supplying water to steam passing through the astern section to limit the exhaust temperature of such steam, and means for supplying condensate from the condenser to the spray device.

3. The combination with a marine turbine having ahead and astern sections, of conduits for supplying steam to the sections, a spray device for supplying water to steam passing through the astern section to limit the exhaust temperature of such steam, a conduit for supplying water 65 to the spray device, valves in the conduits for supplying steam to the astern section and for supplying water to the spray device, and means for interconnecting the valves so that operation of the astern steam valve is accompanied by operation of the valve in the water conduit.

4. The combination with a marine turbine having ahead and astern sections exhausting to a condenser, of conduits for supplying steam to the ahead and astern sections, a spray device for sup- 75

plying water to steam passing through the astern section to limit the exhaust temperature of such steam, a conduit for supplying condensate from the condenser to the spray device, valves in the 5 conduits for supplying steam to the astern section and for supplying condensate to the spray device, and means for interconnecting the valves so that they may be opened and closed together.

5. The combination with a marine turbine having ahead and astern sections with a common exhaust space therebetween and a condenser in communication with the common exhaust space, of means for supplying steam to the ahead and astern sections, a spray device for injecting water 10 into the exhaust space for the purpose of effecting transfer of heat from steam exhausted from the astern section so as to limit the temperature of such steam, and means for supplying water suitable for boiler feed and at approximately the 15 saturated temperature corresponding to the vacuum to the spray device.

6. In a marine turbine, a casing, a rotor within the casing, ahead and astern blading sections carried by the casing and the rotor, said sections 25 having their exhaust ends spaced apart to provide a common exhaust space enclosed by the casing, means for condensing steam supplied to the common exhaust space, a circumferential spray device within the casing and disposed so 30 as to be out of the way of steam discharged from the sections for spraying water into steam exhausting from the astern section to limit the temperature of such steam, and means for supplying water suitable for boiler feed and at approximately the 35 saturated temperature corresponding to the vacuum to the spray device.

7. In a marine turbine installation, a casing, a rotor within the casing, ahead and astern blading sections carried by the casing and by 40 the rotor, means for supplying steam to the ahead and astern sections, a circumferentially extending spray pipe arranged to inject a water spray into steam passing through the astern section, means providing a source of injection water of 45 such temperature that it will not produce undesired chilling of parts of the installation relatively to other parts, and means for supplying water from the source to the spray pipe.

8. In a marine turbine installation, a casing

having upper and lower parts, a rotor within the casing, ahead and astern blading sections carried by the casing and by the rotor, semi-circular spray pipe sections carried by the upper and lower parts of the casing, disposed radially outward of the blading of the sections and arranged to inject a water spray into steam passing through the astern section, means providing a source of water of such temperature that the spray will not produce undesired chilling of parts 10 of the installation relatively to other parts, and means for supplying water from said source to the semi-circular spray pipes.

9. In a marine turbine, a casing, a rotor within the casing, ahead and astern blading sections 15 carried by the casing and by the rotor and having their exhaust ends discharging to a common exhaust space within the casing, means for condensing steam supplied to the exhaust space, a circumferentially extending spray device supported by the casing and disposed radially outward of the blading sections so as to be out of the way of steam exhausted therefrom and arranged to discharge a spray of water into the steam exhausted from the astern section to limit 25 the exhaust temperature of such steam, and means for supplying to the spray device water suitable for boiler feed and at approximately the saturated temperature corresponding to the vacuum.

10. In a marine turbine, a casing having upper and lower parts, a rotor within the casing, ahead and astern blading sections carried by the casing and by the rotor and discharging into a common exhaust space enclosed by the casing, means for condensing steam supplied to the exhaust space, semi-circular spray pipes carried by the upper and lower parts of the casing and disposed adjacent to and radially outward of the discharge 35 end of the ahead section, said semi-circular spray 40 pipes having jets directed toward the discharge end of the astern section so as to supply water to steam exhausting from the astern section in order to limit the temperature of such steam, and means for supplying to the semi-circular spray 45 pipes water suitable for boiler feed and at approximately the saturated temperature corresponding to the vacuum.

WARREN B. FLANDERS.
